(57) **CLAIM**

The ornamental design for a bathing tub table, as shown and described.

DESCRIPTION

FIG. 1 is a perspective view of the bathing tub table of the present invention;

FIG. 2 is a front elevation thereof;

FIG. 3 is a rear elevation thereof;

FIG. 4 is a right-side elevation thereof; and

FIG. 5 is a left-side elevation thereof.

FIG. 6 is a top plan view thereof; and,

FIG. 7 is a bottom plan view thereof.

The bathing tub table of the present invention is designed to be used primarily in a bathing environment for supporting objects such as toys, toiletries, grooming utensils and the like.
